UNITED STATES PATENT OFFICE.

EMILE E. BOUCHARD, OF BURLINGTON, VERMONT.

LUBRICATING AND PROTECTING JACKET FOR SPRINGS.

1,899,248.

Specification of Letters Patent.

Patented Dec. 6, 1921.

Application filed January 24, 1921. Serial No. 439,576.

To all whom it may concern:

Be it known that I, EMILE E. BOUCHARD, a citizen of the United States, residing at Burlington, in the county of Chittenden 5 and State of Vermont, have invented certain new and useful Improvements in Lubricating and Protecting Jackets for Springs; and I do declare the following to be a full, clear, and exact description of the invention, such as will enable others skilled in the art to which it appertains to make and use the same.

This invention relates to an improved lubricating and protecting jacket for application on vehicle leaf springs, the object of the invention, as is obvious, being to provide a device of this class which will effectively house the various leaves of the spring and supply them with a lubricant, prevent 15 foreign matter such as dust and mud from depositing on them, protect them from rusting due to exposure to the weather, and thus increase their life to a great extent.

At the present time, so far as I am aware, 25 patented and marketed devices of this class are constructed in a manner similar to mine but they are usually held in place on the spring by lacing. I find that this particular type of fastening or retaining means for 30 the jacket is undesirable, in that it consumes much time and labor in placing the jacket in position on the spring and permits them to wrinkle to such an extent as to give them an extremely untidy appearance. It 35 sometimes happens that by drawing the lacing sufficiently tight to insure a snug fit of the jacket on the spring to overcome wrinkling is detrimental, as the relative movement of the leaves of the spring often times splits the snugly fitting jacket. Then again, the means employed for drawing the jackets tight and preventing them from 40 moving longitudinally on the spring is such that it interferes with free action of the 45 leaves of the spring.

In view of the above circumstances, I have devised a jacket for the purpose set forth which although similar in general appearance to devices now in use, is an improvement thereon, in that it embodies novel resilient means for connecting the overlapping ends of the jacket together in such a way as to permit them to separate, that is to move apart, to accommodate the relative 50 movement of the leaves of the spring and as soon as the spring assumes its normal or

original position, draws the ends together to insure a tight and snug fit of the jacket at all times. Thus, I provide a jacket which will be neat and attractive in appearance. 60 In addition to employing this novel means for securing the ends of the sheet forming the jacket together, I make use of novel anchoring means for the jackets, this means serving to connect the two jackets on opposite sides of the spring split together and preventing longitudinal shifting and wrinkling of the jacket to a great extent, and at the same time permitting free flattening or straightening of the spring to overcome 65 breaking or splitting of the jacket. By employing my novel retaining means for the jacket and eliminating the lacing usually employed, much time and labor is saved in placing the jacket in position on 70 a spring and this means much to the mechanic during such work. As a matter of fact, all parts employed in the make-up of my jacket are so simple, that unskilled hands will be able to easily and readily apply the 75 jackets on vehicle springs.

The foregoing and other features and advantages of the invention will be apparent during the course of the following description.

In the accompanying drawings forming a 85 part of this specification and in which like numerals are employed to designate like parts throughout the same:

Fig. 1 is an elevational view of one 90 end of a vehicle leaf spring equipped with a jacket constructed in accordance with this invention.

Fig. 2 is a bottom plan view thereof, 95 showing the novel anchoring means and connecting means for the ends of the jacket.

Fig. 3 is a top plan view of the jacket disclosing the approximate shape thereof when laid out flat.

Fig. 4 is a view disclosing a complete 100 spring equipped with two of the jackets showing the manner in which the jackets are connected together.

Fig. 5 is a section taken on the plane of the line 5—5 of Fig. 3.

Fig. 6 is a detail perspective view of one 105 of the resilient connectors for the overlapping ends of the jackets.

In carrying out the invention, I make use of a sheet 1 of suitable weather-proof material, such as leather, which is preferably 110 of the shape disclosed in Fig. 3 but may be

of any other shape so that when it is wrapped around the spring, it will snugly fit the latter. Stitched or otherwise secured to the inner face of this sheet 1 is an absorbent pad 2 which is adapted to contain and dispense a lubricant, it being understood that when the jacket is in place, this pad is in direct contact with the leaves of the spring. This pad and the sheet is wrapped around the spring on opposite sides of the central clips in the manner shown, the ends of the sheet 1 being arranged in overlapping relation. The narrower end of the sheet and pad is, of course, arranged near the adjacent end of the spring to insure a snug fit. As before intimated, I make use of novel resilient means for connecting the overlapping ends of the sheet and pad together. While this means may be of some other construction, I prefer to use coiled springs 3 for the purpose, the ends of these springs being extended beyond the endmost convolutions and being bent to form anchoring hooks 4, the extremities of which are pointed or sharpened as indicated at 5 and adapted to hook into the sheet in the manner shown in Fig. 2. By employing these particular types of connectors, the jacket can be drawn tight by hand before placing them in effective position and all wrinkles can be removed before each connector is hooked into the sheet 1. Thus, a snug fit of the jacket and a neat appearance is insured and wrinkling of the jacket is practically prevented. In addition to employing the novel spring connectors, I also make use of a pair of relatively long coiled springs previously referred to as anchoring means, these springs being designated by the numeral 6. Close examination thereof will disclose the fact that each one is permanently connected to one of the jackets and has at its free end a hook 7 which is designed to engage the adjacent end of the other jacket. In other words, each jacket carries one of these coiled springs 6 and this spring has its free end hooked into the other jacket as disclosed in Fig. 4. It is obvious as before stated, that these springs 6 serve to prevent longitudinal creeping of the jackets and overcome wrinkling, but at the same time, permit sufficient longitudinal movement of the jackets to accommodate the relative movement of the leaves of the spring. While I have shown and described the springs 6 as having their free ends connected to one of the jackets, I wish it to be understood that these ends could be anchored at any suitable place on the spring if so desired.

In use, the pad 2 is saturated with a suitable oil or other lubricant and the jacket is wrapped around the springs on one side of the spring clips bringing the pad into direct contact with the leaves of the spring and permitting the ends of the outer water-proof

sheet to overlap one another, the narrow end of the sheet and pad, of course, being disposed at the adjacent end of the spring. The jacket is drawn tightly about the spring by hand and the pointed hooks of the connectors 3 are anchored or embedded in the jackets, these connectors being disposed transversely of the spring in the manner disclosed in Fig. 2. It may be suggested that it will be well to place the connectors adjacent the ends of the spring in position first and then smooth and draw the jackets tightly around the spring and place the remaining connectors in position from the end of the spring toward the center of the latter. In this way, wrinkling of the jackets can be practically overcome and a neat appearance insured. After the two jackets are in place, the hooks 7 of the springs 6 are connected to the proper jackets in order to prevent longitudinal creeping of the jackets. It is hardly necessary to again direct attention to the fact that the employment of these particular kinds of retainers or connectors overcomes the possibility of the jackets splitting or breaking since free relative movement of the leaves of the spring is permitted, which is not the case with the ordinary types of jackets now on the market. The jackets can be applied on the spring in little or no time and the person applying them need not be experienced in the least. When the jacket is in place, it will insure thorough lubrication of the leaves of the spring and prevent the depositing of dust, mud, or other extraneous matter thereon. In case the spring should become broken from a sudden jar, the jackets can be easily and readily removed to permit the necessary repairs to be made.

A careful consideration of the foregoing description taken in connection with the drawings is thought to be sufficient to enable persons skilled in the art to which the invention relates to obtain a clear understanding of the same and to appreciate the advantages gained by this particular construction and arrangement. Therefore, a more lengthy and detailed description is thought unnecessary.

Although advantageous and effective results are practically insured with the construction and arrangement herein shown and described, I wish it to be understood that slight changes in the shape, size, and arrangement of parts may be resorted to within the scope of the subjoined claims.

I claim:

1. A lubricating and protector jacket for vehicle leaf-springs comprising a sheet of flexible weather-proof material, a pad of absorbent material secured to the inner face thereof and adapted to contain and dispense a lubricant, resilient means for connecting the ends of said sheet together, and a re-

silient anchor for one end of the jacket to prevent wrinkling and longitudinal movement thereof.

2. The combination with a leaf-spring for vehicles; of a pair of lubricating and protecting jackets fitted thereon on opposite sides of the usual central clip, and a pair of coiled springs, each one being connected at one end to one of the jackets and having a hook at its opposite end to engage the other jacket.

3. A vehicle spring lubricating and protecting jacket comprising a sheet of flexible and moisture-proof material including a lubricating surface adapted to be wrapped rather snugly around the spring with its

ends arranged in overlapping relationship, coiled springs having their ends bent to provide hooks, said springs being arranged transversely across the jacket and having 20 their hooks engaged with the overlapped ends of said jackets to connect said ends together, but permit them to separate to accommodate the relative movements of the various spring leaves, and a resilient anchor 25 for the inner end of the jacket, serving to prevent wrinkling of the latter and to prevent longitudinal slipping thereof.

In testimony whereof I have hereunto set my hand.

EMILE E. BOUCHARD.
